PACKAGE SEALING MACHINE

Parvin Wright, Seattle, Wash.

Application June 8, 1937, Serial No. 147,117

22 Claims. (Cl. 81—9.1)

This invention relates to box strapping machines and has for its object to provide a mechanism which is simple in construction and operation, and more efficient in use than those hereinafter proposed.

With these and other objects in view the invention resides in the novel details of construction and combinations of parts as will be disclosed more fully hereinafter and particularly 10 pointed out in the claims.

Referring to the accompanying drawings forming a part of this specification and in which like numerals designate like parts in all the views,—

Fig. 1 is a vertical sectional view of the machine taken substantially in the plane of the strap with which a box is to be bound;

Fig. 2 is a vertical sectional view of the machine taken transversely of Fig. 1 and substantially on the line 2—2 of Fig. 4 looking in the direction of the arrows;

Fig. 3 is a view somewhat similar to Fig. 2 but taken as on the line 3—3 of Fig. 1 and looking in the direction of the arrows, but illustrating the crimping jaws in their lowermost position;

Fig. 4 is a horizontal sectional view taken substantially on the line 4—4 of Fig. 1 and looking in the direction of the arrows;

Fig. 5 is a detail view partly in elevation and partly in section to illustrate the construction and 30 operation of the strap cutter;

Fig. 6 is a fragmentary central sectional view of the yieldable connection provided in the link for actuating the means for feeding a strip of band material to the seal forming mechanism.

Fig. 7 is a perspective view of a formed seal blank;

Fig. 8 is a fragmentary plan view of the overlapped ends of the box strap with a crimped seal applied thereto for locking the same together;

Fig. 9 is a fragmentary perspective view of one of the crimping jaws;

Fig. 10 is a detail view illustrating how the crimping jaws secure a seal to the tensioned box strap;

Fig. 11 is a detail vertical sectional view of a portion of the feeding means for moving a supply of band material to the seal forming mechanism; and

Fig. 12 is a vertical sectional view taken as on the line 12—12 of Fig. 11 and looking in the direction of the arrows.

This invention is directed to machines for tensioning a thin flat metallic strap around a box or crate, forming a seal from a supply of thin flat metallic band material, and applying and crimping

the formed seal around the overlapping ends or bights of the box strap, the crimping operation being performed simultaneously with the cutting and forming of a seal, which seal however, is for subsequent use in the next box strapping and sealing operation.

1 indicates generally the base of the machine which has at its substantially central portion a vertically extending housing generally identified by the numeral 2 for containing a loose coil 10 of seal forming band material 3 the outermost end of which is fed intermittently to and over an anvil 4 disposed at what will be termed the front edge 5 of the machine, the feeding action being stopped when the end of said material strikes the shoulder 6 of a dog 7 pivoted as at 8 to the front cover 9 of said housing, said dog placed under tension as by the spring 10 so as to hold against retrograde movement the free end of the seal band against the top surface of said anvil. In this 15 respect said dog is rounded where it engages said seal band so that the latter may be freely directed between said dog and said anvil in the forward feeding of the seal band material.

Said housing 2 comprises the front plate 9 extending vertically and having its side edges suitably secured to the two side walls such as 11 and 12 the latter of which is preferably removable but secured in place as by the screws 13 to portions of the machine casting, the rear of said 20 housing preferably being open but covered by a hinged door 14 made of spring material, said door pivoted at 15 and provided with a latch-forming end 16 for making possible the ready insertion of a new coil of seal forming band material when the previously contained coil has been used up, a sight opening 17 being provided in one or both of the side walls 11 and 12 to enable the operator to determine the quantity of seal forming band 25 material left in the housing.

At the front end of the machine there is provided a vertically reciprocable plunger 20 operating closely in a suitable guide space formed between the housing walls 9, 11 and 12 and a portion 21 of the machine casting. This plunger comprises a base portion 22 carrying at its lower end a hardened shear member 23 which, upon its downward movement, cuts off the free end of the seal forming material lying on the anvil 4, said base portion carrying at its upper end two parallel spaced plates 24 and 25 carrying therebetween a plurality of hardened rods such as 26 spaced from each other to receive therebetween the teeth such as 27 carried by the lever or handle 28 pivoted as at 29 in the upper portion of the ma- 30 35 40 45 50 55

chine, wherefore it will be seen from Fig. 2 that as said lever is oscillated the plunger will be given vertical reciprocation or sliding movement. Further, the bottom of the base member 22 of said plunger has a configuration as at 38 coacting with the configuration of said anvil so that when the free end of the seal forming band material is cut off, by the shear 23, it is immediately and subsequently bent over the anvil to assume the shape shown in Fig. 7 but is still retained on the anvil by pressure of the holding dog 7, said member 22 having a slotway 31 formed therein to straddle said dog during this seal blank forming operation.

The base portion 22 of the plunger is preferably made of solid metal for strength and securely threaded thereto is a pin generally indicated by the numeral 35 extending horizontally outward therefrom through a vertical slotway 36 formed in the side 12 of the housing, said pin having the same diameter throughout its length, or made of different diameters as found most suitable, the latter being the case illustrated in the drawings, this pin having reciprocation with the plunger. The function of this pin is to actuate the crimping dogs, later to be described, as well as the cutter for severing the bight of box strap between the supply thereof and the crimped seal, said pin also actuating the means for feeding the seal blank forming material to the anvil 4.

Guides 37 and 38 are suitably secured to the walls of the housing 2 to permit vertical reciprocation therein of a plate 39 which, with a plate 40 parallelly spaced therefrom, constitutes a frame for pivotally supporting as at 41 and 42 an opposed pair of crimping jaws 43 and 44, the pivot pins 41 and 42 together with a stop pin 45 serving to hold the frame plates 39 and 40 in spaced relation. The upper extremities of the jaws 43 and 44 are connected as by the links 46 and 47 to the plunger pin 35 wherefore it will be clearly understood that the reciprocations of said pin will cause the crimping jaws to operate about their pivots while carrying said jaws in their frame upwardly and downwardly in the guides 37 and 38, the top edge of the plate 39 being provided with a slot 48 to accommodate the pin 35 in its extreme lower position. In other words, the jaws 43 and 44 with their links 46 and 47 create a toggle, actuated by the plunger pin 35, so that when said pin is in its elevated position the lower ends of the jaws will be fully opened but when said pin is in its lowermost position the shoulders such as 49 of said jaws will have come to rest on the seal blank to be crimped, and further downward movement of the pin 35 causes an outward flexing of said links to turn the jaws about their pivots to fold the depending sides such as 50 of the seal blank in under the lowermost bight 51 of the box strap, this final action of said jaws causing suitable projections 52 on the inner surfaces thereof to bite into the opposite edges of the overlapped bights to make deformations indicated at 53 preventing slippage of one bight of the box strap over the other bight after the seal is completed.

A stirrup 60 is disposed within the housing 2 and pivoted at its upper ends as at 61 to the opposite sides 11 and 12 of said housing, said stirrup being of substantially U-shape with a bottom wall 62 connecting the two vertical spaced sides. The coil 8 of the seal forming band material is located between the sides of this stirrup, the outer end of said coil passing to the anvil 4 over the top surface of the lower wall 62 of said stirrup. A pin 63 passes transversely of

the stirrup adjacent its lower wall, and is pivotally mounted in the opposed sides, said pin extending outwardly of the housing through a slot 64 formed in the side wall such as 12 thereof, and secured to the outer end of this pin is an arm 65 pivotally connected as at 66 to one end of a tubular member 67 slidably receiving therein in one end of a rod 68 whose other end is pivotally mounted on the plunger pin 35. The end of said rod within the tubular member is fashioned to form a seat against which abuts one end of a coil spring 69 whose other end is retained as by a cap 70 for the tubular member, see particularly Fig. 6, the purpose of this construction being to provide a yieldable connection between the plunger pin 35 and the arm 65.

On the pin 63 is secured a dog 71 which, when the arm 65 is pulled by the plunger pin 35 in a direction toward the front of the machine and given slight rotary movement thereby, will pinch the outer end portion of the seal forming band material against the bottom wall 62 of the stirrup and feed said portion over the anvil 4 until the extreme end is stopped by the shoulder 6 of the holding dog 7, see Fig. 2. On the reverse or backward movement of said arm 65 the dog 71 will be lifted from its pinching position, leaving the end of the seal forming band material on said anvil, the stirrup 60 being swung toward the left as seen in Fig. 2 to the limit of its movement caused by the downward movement of the plunger pin. On the next upward movement of said plunger pin the stirrup dog 71 will again take a pinch-hold on another portion of the seal forming band material and similarly feed it toward the anvil 4. In the meantime the shear 23 carried by the plunger will have severed the end portion of the previously forwardly fed seal forming band material and this severed portion will have been moved out of the way by mechanism 40 later to be described. In other words the stirrup dog 71 has intermittent pinching action on the coiled band material for successively feeding said material to a position under the plunger for severance of the end portion of said material by the shear 23. The spring 69 is provided to permit continued movement of the rod 68 during the extreme upward movement of the plunger pin 35 after the end of the seal forming band material has reached and been stopped by the shoulder 6 of the holding dog 7.

Substantially parallel with the front edge 5 of the machine, there is formed in the base 1 a guideway 75 to receive therein the slide 76 carrying at one end an upstanding lug 77 to which is pivoted as at 78 one end of a link 79 the other end of which is pivoted as at 80 to a vertically extending hand lever 81 the lowermost end of which is fulcrumed as at 82 to an ear 83 extending upwardly from the base of the machine, so that when the lever 81 is oscillated the link 79 will cause horizontal reciprocations of the slide 76.

The opposite end of said slide has an upstanding lug 84 to which is pivoted as at 85 a tensioning or take-up dog 86 having a handle portion 87 and urged as by the spring 88 against the bight of the box strap to pinch the same against a cooperating foot 89. This lug 84 has rigidly attached thereto a pair of fingers 90 and 91 substantially parallel to each other and to said slide, said fingers extending in a direction from said lug toward the anvil 4, said fingers being so spaced from each other and positioned as to strike and slide the formed seal blank to the 75

left as seen in Fig. 1 from the anvil 4 onto and straddling the upper bight 92 of the overlapped ends of the box strap, and into a position immediately below and in the path of the crimping jaws.

The base 1 of the machine is also provided with another upstanding ear 100 having a horizontal lateral extension 101 serving as a foot or shelf upon which the upper bight 92 of the box strap is held. To said ear 100 is pivoted as at 102 a dog 103 for pinching said upper bight of the box strap and holding the same against the upper surface of said foot, said dog having a downward projection 104 for engaging the side edge of the upper bight of the box strap and preventing said bight from moving in a direction away from the front edge 5 of the machine. Said dog has an upwardly extending handle portion 105, and a pin 106 extending from the side of the ear 100 15 serves as a stop for limiting the movement of said dog in one direction. Said ear has a second dog 107 pivoted thereto as at 108 also having an upwardly extending handle portion 109, the two handle portions 105 and 109 being spaced 20 from each other in a plane substantially parallel with the front edge 5 of the machine, with a spring 110 interposed between said handles for exerting a pressure normally tending to move the two dogs 103 and 107 in a direction toward 25 each other as will be clear from Fig. 1. The dog 107 is adapted to pinch and hold the lower bight 51 of the box strap against the upper surface of a toe 111 extending forwardly from the front edge of the base of the machine, the lower 30 end portion of said dog 107 being L-shaped to clear the upper bight 92 while its extreme lower end extends into the space between the upper and lower bights for engaging the lower bight.

Secured to the ears 83 and 100, and bridging the slide 76 is a vertical plate 115 whose extreme forward edge is fashioned into a lower cutter blade 116 cooperating with an upper cutter blade 117 constituting one arm of a crank 118 pivoted to said plate as at 119, the other arm of said 45 crank having formed therein a slotway 120 within which rides the plunger pin 35. With particular reference to Fig. 5 it will be seen that this slotway is provided with a bend indicated at 140 to insure operation of the cutter blades 50 before pin 35 reaches the lower limit of its stroke. The position of these two cutter blades is such as to receive therebetween the upper bight 92 of the box strap so that, after the strap has been tensioned about the box, the upper bight thereof 55 will be severed at about the midpoint of the downward movement of the plunger pin, thereby permitting the severed bight (with the formed seal blank thereon) to be moved into surface contact with the lower bight 51 by the crimping jaws 60 during the remainder of the down stroke of said pin, the final oscillation of said jaws to crimp the formed seal blank and the contacting bights 65 securely together taking place just prior to the lowermost limit of said stroke.

The operation of the machine will be briefly described in the following. The coil of seal forming band material 3 is placed within the housing 2 and the outer end of the coil is threaded under the dog 71 of the stirrup 68, and then the handle 73 70 is partially oscillated to give short reciprocations to the plunger 20 until the yieldable connection 67-68 has caused intermittent feed of said end to and against the shoulder 6 whereupon the dog 7 will hold said end against the anvil 4, the handle 28 then being substantially

in the position shown in Fig. 2 with the plunger 20 raised to its uppermost throw. Then the handle 28 is fully oscillated to the position shown in Fig. 3 which causes a downward throw of said plunger during which movement the shear 23 5 will cut off the correct length from the end portion of the coil and the lower end of the plunger will form the severed portion into the seal blank having a substantially inverted U-shape, and leave this formed blank held upon the anvil 4 10 by the dog 7. The stirrup 68 will then be in its rearmost position as indicated in Fig. 3.

The machine is then placed on the upper surface of the box to be strapped, and a length of strap from a coiled supply led to the machine 15 where the extreme end portion 121 of said strap is laid on the upper surface of a toe 122 extending forwardly from the front edge of the base of the machine and under or in line with the plunger 20. The strap in this position is passed beneath 20 the lower cutter blade 116 in a space provided therefor, and thence placed between the dog 107 and the top surface of the cooperating toe 111, the dog being oscillated by the handle 109 to permit entry thereunder of the strap, see Fig. 1. 25 The strap is then passed around the box as will be clearly understood and threaded under the dog 86 carried by the slide 76 so that said dog, under the tension of its spring 88, will grip said strap and pinchingly hold it against the top surface of its cooperating foot 89. The remainder of the strap is laid in the slot 123 formed beneath a portion of the anvil 4, thence passed between the cutter blades 116 and 117 (the crimping jaws being raised for this purpose) and 30 thence passed over the lateral lower extension of the dog 107, and placed between the dog 103 and its cooperating foot 101.

Then the tensioning lever 81 is oscillated, causing reciprocation of the slide 76 carrying the tensioning dog 86, and when the slide moves to the left as seen in Fig. 1 the dog 86 and its cooperating foot 88 will pull the slack out of the strap around the box because the lower bight 51 of said strap is firmly gripped by the dog 107 carried by the base of the machine. If the strap has been applied manually around the box initially with sufficient tautness, one complete throw of the lever 81 might be sufficient but plural oscillations of said lever may be made if necessary to get 50 the desired tension, the function of the dog 86 being to progressively tighten the strap around the box, and the function of the dog 103 being to hold the tightened strap should plural reciprocations of the slide be necessary. When the 55 desired tension is obtained, the dogs 103 and 107 will maintain said tension and the lever 81 may be raised to its vertical position causing the slide to move to its extreme right hand position, looking at the machine as in Fig. 1, thereby moving 60 the fingers 90 and 91 out of the plunger chamber; with the slide in this position its dog 86 will clampingly hold the tensioned strap so that the upper bight 92 may be subsequently severed by the cutter blades 116 and 117 without loss of strap 65 tension.

During the left hand movement of the slide 76 the fingers 90 and 91 carried thereby will have moved or slid the formed seal blank from the anvil 4 onto and straddling the upper bight 92 70 of the tensioned strap and into a position immediately below the crimping jaws. When the desired strap tension is obtained the other handle or lever 28 is given an oscillatory movement from the position shown in Fig. 2 to the position shown 75

in Fig. 3 thereby lowering the plunger 20 carrying the pin 35 which actuates the cutter blade 117 to sever the upper bight of the strap, which severance is immediately followed by the full outward toggle movement of the links 46 and 47 to bring together the crimping jaws 43 and 44, thereby completing the seal shown in Fig. 8. Upward movement of the plunger then releases and raises the crimping jaws, and the machine 10 may then be removed from the box.

Whereas the lower portion of the plunger 20 has been illustrated as formed with a separable shear element 23 it will be understood that this shear could be an integral part of the plunger 15 hardened or tempered to perform its cutting function. Also the means for forming the seal blank from the strip material comprises the stationary anvil 4 constituting a male die and the correspondingly formed bottom portion of the 20 plunger constituting a female die, both dies co-operating with the plunger for severing a predetermined length of the fed strip material and forming the severed portion into the seal blank.

Special attention is directed to the means for 25 reciprocating the plunger which comprises the rods 26 constituting rack-like elements, and the teeth 27 for engagement therewith. These teeth are arranged eccentrically with respect to the pivot 29 of the operating lever 28 so as to dispose 30 the "tooth valley" 135 closer to the pivot than any of the other valleys. Further, the rods 26 are arranged in a row which is not parallel to a face of the plunger but which is obliquely disposed to the line of plunger reciprocation, the 35 topmost rod 136 passing closest to the lever pivot 29 on the downward stroke of the plunger, and this particular rod may be provided as shown with a cylindrical bushing constituting a fairly frictionless bearing with the toothed portion of 40 said lever. The purpose of this construction is to give increased leverage (see Fig. 3) upon the plunger at the end of its downward movement at the time not only when the strip material is severed and formed into the seal blank, but when 45 the upper bight 92 of the box strap is severed from its supply, and the crimping jaws 43 and 44 perfect the seal.

It will be obvious that those skilled in the art 50 may vary the details of construction and arrangements of parts without departing from the spirit of the invention and therefore it is desired not to be limited to the exact foregoing disclosure except as may be demanded by the claims.

What is claimed is:

1. In a box strapping machine the combination of strap tensioning means; means to feed a strip of seal blank material in a direction transverse to the movement of the strap tensioning means; a reciprocable plunger and means cooperating therewith to sever a predetermined length of the fed strip of material and to form the severed portion into a seal blank; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

2. In a box strapping machine the combination of strap tensioning means; yieldable means to feed a strip of seal blank material in a direction transverse to the movement of the strap tension-

ing means; a reciprocable plunger and means co-operating therewith to sever a predetermined length of the fed strip of material and to form the severed portion into a seal blank; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

3. In a box strapping machine the combination of strap tensioning means; means to feed a strip of seal blank material in a direction transverse to the movement of the strap tensioning means, said feeding means including a pivoted member; a reciprocable plunger and means co-operating therewith to sever a predetermined length of the fed strip of material and to form the severed portion into a seal blank; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

4. In a box strapping machine the combination of strap tensioning means, means to feed a strip of seal blank material in a direction transverse to the movement of the strap tensioning means, said feeding means including a pivoted member provided with a gripper element engageable with the strip; a reciprocable plunger and means co-operating therewith to sever a predetermined length of the fed strip of material and to form the severed portion into a seal blank; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

5. In a box strapping machine the combination of strap tensioning means; means to feed a strip of seal blank material in a direction transverse to the movement of the strap tensioning means, said feeding means including a swingable stirrup through which the strip is threaded, and a gripper element carried by said stirrup and engageable with the strip; a reciprocable plunger and means cooperating therewith to sever a predetermined length of the fed strip of material and to form the severed portion into a seal blank; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

6. In a box strapping machine the combination of strap tensioning means; means to feed a strip of seal blank material in a direction transverse to the movement of the strap tensioning means; a reciprocable plunger and means cooperating

therewith to sever a predetermined length of the fed strip of material and to form the severed portion into a seal blank, the cooperating means including two die members one of which constitutes a shear element; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

7. In a box strapping machine the combination of strap tensioning means; means to feed a strip of seal blank material in a direction transverse to the movement of the strap tensioning means; a reciprocable plunger and means cooperating therewith to sever a predetermined length of the fed strip of material and to form the severed portion into a seal blank, the cooperating means including a stationary die member and a companion die member carried by the plunger, one of said members constituting a shear element; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

8. In a box strapping machine the combination of strap tensioning means including a reciprocable slide; means to feed a strip of seal blank material in a direction transverse to the movement of the strap tensioning means; a reciprocable plunger and means cooperating therewith to sever a predetermined length of the fed strip of material and to form the severed portion into a seal blank; means actuated by the strap tensioning means and carried by said slide to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

9. In a box strapping machine the combination of strap tensioning means; means to feed a strip of seal blank material in a direction transverse to the movement of the strap tensioning means; a reciprocable plunger and means cooperating therewith to sever a predetermined length of the fed strip of material and to form the severed portion into a seal blank; means actuated by the strap tensioning means to move the formed seal blank into crimping position with respect to overlapped portions of the tensioned strap; and means actuated by said plunger and including a plunger carried pin for operating the material feeding means, for crimping the positioned seal blank about overlapped portions of the tensioned strap to form a seal, and for cutting off the surplus of the strap adjacent the seal.

70 10. In a box strapping machine the combination of strap tensioning means; means to feed a strip of seal blank material in a direction transverse to the movement of the strap tensioning means; a reciprocable plunger and means coop-

erating therewith to sever a predetermined length of the fed strip of material and to form the severed portion into a seal blank, said plunger having rack-like elements; means to reciprocate said plunger, said means having a toothed portion operatively engaging said rack-like elements; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

11. In a box strapping machine the combination of strap tensioning means; means to feed a strip of seal blank material in a direction transverse to the movement of the strap tensioning means; a reciprocable plunger and means cooperating therewith to sever a predetermined length of the fed strip of material and to form the severed portion into a seal blank, said plunger having rack-like elements; pivoted means to reciprocate said plunger, said means having a toothed portion operatively engaging said rack-like elements, said portion eccentrically disposed with respect to the pivot of said means; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

12. In a box strapping machine the combination of strap tensioning means; means to feed a strip of seal blank material in a direction transverse to the movement of the strap tensioning means; a reciprocable plunger and means cooperating therewith to sever a predetermined length of the fed strip of material and to form the severed portion into a seal blank, said plunger having rack-like elements arranged in a row obliquely disposed to the line of plunger reciprocation; means actuated by the strap tensioning means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

13. Mechanism for forming a seal blank for sealing box straps or the like, comprising means to feed strip material to a position where the seal blank is formed; a reciprocable member including means to sever the end portion of the strip and to form the severed portion into the seal blank, said member actuating the strip material feeding means; means to hold the seal blank temporarily after its formation; and means to move the seal blank from its temporarily held position.

14. Mechanism for forming a seal blank for sealing box straps or the like, comprising means to feed strip material to a position where the seal blank is formed; a reciprocable member and cooperating means to sever the end portion of the strip and to form the severed portion into the seal blank; pivoted constantly tensioned pressure means to hold the seal blank temporarily after

its formation; and means to move the seal blank from its temporarily held position.

15. Mechanism for forming a seal blank for sealing box straps or the like, comprising means to feed strip material to a position where the seal blank is formed; a reciprocable member including means to sever the end portion of the strip and to form the severed portion into the seal blank, said member actuating the strip material feeding means; means to hold the seal blank temporarily after its formation; and means to move the seal blank from its temporarily held position, said means subject to actuation when the seal blank is required for sealing the box strap.

16. Mechanism for forming a seal blank for sealing box straps or the like, comprising means to feed strip material to a position where the seal blank is formed; a stop for limiting the feeding movement of the strip to provide a predetermined length for seal blank formation; a reciprocable member including means to sever the predetermined fed length of the strip and to form the severed portion into the seal blank, said member actuating the strip material feeding means; means to hold the seal blank temporarily after its formation, said means carrying said stop; and means to move the seal blank from its temporarily held position.

17. Mechanism for forming a seal blank for sealing box straps or the like, comprising means to feed strip material to a position where the seal blank is formed; a stop for limiting the feeding movement of the strip to provide a predetermined length for seal blank formation; a reciprocable member and cooperating means to sever the predetermined fed length of the strip and to form the severed portion into the seal blank; means to hold the seal blank temporarily after its formation, said means having said stop as an integral part thereof; and means to move the seal blank from its temporarily held position.

18. In a box strapping machine the combination of means to tension a strap about a box; means to form a seal blank for sealing together the ends of the tensioned strap; means actuated

by the tensioning means to move a formed seal blank into position for sealing the tensioned strap; and sealing means actuated by the seal blank forming means.

19. In a box strap sealing machine the combination of means to hold the ends of a box-en-circling strap in overlapped relation; means to form a seal blank for sealing together the overlapped ends of the strap; means to move a formed seal blank into sealing position; and sealing means carried and actuated by the seal blank forming means.

20. In a box strapping machine the combination of strap tensioning means; means to feed a strip of seal blank material to a position for forming a seal blank therefrom; a reciprocable plunger and means cooperating therewith to sever a predetermined length of the fed strip of material and to form the severed portion into a seal blank; means to move the formed seal blank into crimping position with respect to overlapped portions of the tensioned strap; and means actuated by said plunger for operating the material feeding means, for crimping the positioned seal blank about overlapped portions of the tensioned strap to form a seal, and for cutting off the surplus of the strap adjacent the seal.

21. In a box strapping machine the combination of means to hold a strap around a box in sealing position; seal blank feeding and forming means; means to secure overlapped portions of the held strap with a formed seal; a strap cutter; and a reciprocable member including means carrying and directly actuating the seal blank feeding and forming means, the seal securing means, and said cutter.

22. In a box strapping machine the combination of means to hold a strap around a box in sealing position; seal blank feeding and forming means; means to secure overlapped portions of the held strap with a formed seal; and a reciprocable member including means carrying and directly actuating the seal blank feeding and forming means, and the seal securing means.

PARVIN WRIGHT.
